UNITED STATES PATENT OFFICE.

SKIDMORE O'HARA, OF WALTHAM, MASSACHUSETTS, ASSIGNOR TO O'HARA WALTHAM COMPANY, OF WALTHAM, MASSACHUSETTS, A CORPORATION OF MASSACHUSETTS.

PRINTING MACHINE.

Application filed July 8, 1897. Serial No. 204,271

The invention relates to an improvement in machines for printing. It is especially applicable to machines for printing or embossing on glass, china, porcelain, enamelled goods 5 or other frangible articles but it is not limited to use in printing on articles of that particular character. It relates especially to machines in which the printing member has a surface on which the character, marking or 10 design is printed or embossed by a die in such manner that the printing member is adapted to transfer said design to the work.

The invention will be fully understood from the following description when taken 15 in connection with the accompanying drawings and the novel features thereof will be pointed out and clearly defined in the claims at the close of this specification.

In the drawings:

20 Fig. 1 is a fragmentary side elevation partly in diagram of a machine embodying the invention, showing the printing member in position to be operated to engage the die.

25 Fig. 2 is a similar view showing the printing member after having received the impression from the die and turned into position to be operated to print the design on the work.

Fig. 3 is a section on line 3—3, Fig. 1.

30 Referring to the drawings, there is shown at 10 a portion of the frame to hold the working parts. Slidably mounted in a guideway in the frame 10 is a die carrier 11 on the underside of which is mounted a die 12 on which is engraved or embossed the design of whatever nature is intended to be printed upon the work. Said carrier 11 is slidably horizontally 35 to bring the die into operative position as shown in Fig. 1 and also to move it backward from said position at the proper time to bring the die into engagement with the inking roll 13. Any suitable mechanism may be employed for giving reciprocating movement to the die carrier. As shown in the drawings, 40 the said carrier has a portion formed with teeth 14 on its underside engaged by a pinion 15 which may be operated by any suitable means to move the slide carrier forward and back. Preferably a wiper 16 is provided to 45 wipe off the surplus ink from the die.

50 A bracket 17 is secured to the frame having a lower bifurcated portion forming downwardly extending arms 18, 18' in which are journalled a rocker shaft 19 on which are 55 mounted respectively an arm 20 which carries

the printing member and an operating arm or lever 21 by which the printing member is actuated. Said two arms 20 and 21 are respectively made fast to the shaft 19 by the set screws 22 and 23.

60 The arm 20 is of angular shape having an upturned portion 20' having at its upper end a holder 9 for the printing member 24. Preferably said printing member consists of a pad of gelatin or other suitable material adapted to receive an ink impression of the design from the previously inked die 12 when the printing pad is pressed against said die.

65 At 25 is shown a mount for the work having attached to its upper surface a work holder 26 adapted to hold a piece of work W positioned thereon. The work support 25 is 70 slidably in a guideway 28 in the frame so that the work holder may be moved into operative position for the work to receive the impression 75 from the printing member and may be moved out of such position after being printed to permit the printing member to be swung around to engage the die. In Fig. 1 the work holder is shown out of operative position and the die in position to be engaged by the printing member.

80 It is desirable that means should be provided for locking the shaft on which the printing member and the operating handle are mounted in the positions shown in full lines in Figs. 1 and 2 so that when desired they may be left in either of said positions temporarily without being displaced. For 85 this purpose the arm 18 is formed with a socket 29 in which is mounted a spring seated pin 30. The hub 31 of the arm 20 which carries the printing member is formed with two recesses *a* and *b* diametrically opposite each other with which respectively 90 said spring pin 30 is adapted to engage when said arm is in the positions shown in Figs. 1 and 2. When it is in the position shown in Fig. 1, the said pin will engage with the recess *a* and when it is in the position shown in Fig. 2, said pin will engage with the recess *b*. On account of the rounded end of the pin, the pin will be easily disengaged 95 from said recesses whenever a slight pressure is applied to the lever to rotate the rocker shaft 19 and arm 20 and the printing member, and said pin will snap into the recess when the said shaft and arm 20 have been 100 rotated far enough to bring the pin 30 into alignment with either one of said recesses. 105

In operation, assuming that the die 12 has already been inked and brought into operative position as shown in Fig. 1, the lever 21 is pushed downward to bring the printing member 24 into the dotted line position in contact with the die so as to receive the design printed or otherwise transferred thereto by the die in such manner that the said printing member may transfer the design to the work. The lever 21 will then be operated to depress the printing member from the dotted line position shown in Fig. 1 into the full line position shown in Fig. 2, thereby rotating the shaft and bringing the printing member into the elevated position above the plane of the work. The work holder 25 will then be moved to the right from the position shown in Fig. 1 into the position shown in Fig. 2 to bring the work holder and work into alinement with the printing member, the work having previously been positioned on the work holder. The lever 21 will then be pushed up into the position shown in dotted lines in Fig. 2, thereby moving the arm 20 and the printing member downward to print the design upon the work. The operating lever will then be moved from the dotted line position to the full line position shown in Fig. 2 where it will be locked by the pin 30 and the work holder will be moved again to the left into the position shown in Fig. 1. In the meantime the die carrier will have been moved to the right so as to be inked and then moved back again to the position shown in Fig. 1, the work holder being at that time out of the way of the printing member. The operating lever may then be actuated to move the printing member up into contact with the die to be again inked by the die ready for another printing operation.

What I claim is:

1. In a printing machine a die, a work support, a printing member mounted on an arm pivoted intermediate the die and the work support, a lever whereby the said arm may be swung on its pivot to move the printing member in a curved path in a vertical plane, said die and work support being so positioned that the lever is operative to press the printing member up against the die and to move the printing member around to position where it is operative to press the printing member down against the work on the work support.

2. In a printing machine, a die, a work support, a printing member mounted on an arm pivoted intermediate the die and the work support, a lever whereby the said arm may be swung on its pivot to move the printing member in a curved path in a vertical plane, said die and work support being so positioned that the lever is operative to press the printing member up against the die and to move the printing member around to posi-

tion where it is operative to press the printing member down against the work on the work support, said work support being movable out of operative position with relation to the printing member to permit turning of the printing member arm on its pivot from operative position with relation to the work and to permit turning of the printing member back again into operative position with relation to the die.

3. In a printing machine, a die, a work support, a printing member mounted on an arm pivoted intermediate the die and the work support, a lever whereby the said arm may be swung on its pivot to move the printing member in a curved path in a vertical plane, said die and work support being so positioned that the lever is operative to press the printing member up against the die and to move the printing member around to position where it is operative to press the printing member down against the work on the work support, said work support being movable out of operative position with relation to the printing member to permit turning of the printing member arm on its pivot from operative position with relation to the work and to permit turning of the printing member back again into operative position with relation to the die, and means for locking the printing member arm so as to hold the printing member in a stationary position away from the die and away from the work support.

4. In a printing machine a die, a work support, a printing member mounted on an arm which is pivoted on a horizontal axis, said arm be rotatable on said axis to move the printing member up against the die and to swing around into another position where it is operative to press the printing member down against the work on said support.

5. In a printing machine, an arm rotatable on a horizontal axis, a printing member mounted on said arm at some distance from the axis of rotation whereby the rotation of said arm rotates said printing member in a circular path in a vertical plane and carries it from one side to the other of said axis, a die and a work support on opposite sides of said axis of rotation and means whereby said arm may be actuated to press the printing member against the die when the printing member is on one side of said axis and to bring the printing member into engagement with the work on the opposite side of said axis.

6. In a printing machine, an arm pivoted to swing in a vertical plane, a printing member supported on said arm at some distance from the pivot whereby when said arm is rotated said printing member will be moved in a curved path in a vertical plane, a lever adapted to actuate said arm and printing member, a movable die and a movable work

support, said die and work support being so disposed with relation to each other and to the arm which carries the printing member that the lever may be operated to press the printing member up against the die to receive the design therefrom, said lever being operable to swing the printing member to a position on the opposite side of the pivot and press the printing member down upon the work mounted on said work support, said die being movable to and away from opera-

tive position with relation to the printing member, said work support being movable to position the work where the printing member after it has been moved into operative 15 position may be pressed down upon the work, said work support being movable out of operative position to permit the printing member to be swung around into operative position with relation to the die. 20

In testimony whereof I affix my signature.
SKIDMORE O'HARA.
